F. BINN,
FIRE POKER AND CLINKER PICKER.
APPLICATION FILED APR. 4, 1917.

UNITED STATES PATENT OFFICE.

FRANKLIN BINN, OF TRENTON, NEW JERSEY.

FIRE-POKER AND CLINKER-PICKER.

1,254,765.

Specification of Letters Patent. Patented Jan. 29, 1918.

Application filed April 4, 1917. Serial No. 159,838.

To all whom it may concern:

Be it known that I, FRANKLIN BINN, a citizen of the United States, residing at Trenton, in the county of Mercer and State of New Jersey, have invented certain new and useful Improvements in Fire-Pokers and Clinker-Pickers, of which the following is a specification, reference being had to the accompanying drawings.

10 This invention relates to pokers, and the general object of the invention is to provide a poker so constructed that it may be used not only for the ordinary purpose for which a poker is used, but may also be used for 15 picking out clinkers, or any other objects which may accidentally fall on a bed of coals.

A further object of the invention is to provide a combined poker and clinker 20 picker, including members slidably connected to each other and having coacting jaws, the spring urging the jaws to a closed position, and means whereby the jaws may be moved bodily away from each other to open 25 them, so that they may grasp an object.

Other objects will appear in the course of the following description.

My invention is illustrated in the accompanying drawings, wherein:

30 Figure 1 is a side elevation of my improved poker, the tubular member being in section;

Fig. 2 is a like view of a modified form of my invention;

35 Fig. 3 is a like view of another modified form;

Fig. 4 is a cross section on the line 4—4 of Fig. 1.

Referring to these figures, and more particularly to Fig. 1, 10 designates the shank of a poker, which is angularly bent at one end as at 11 to form a jaw, the inner face of this jaw being serrated or otherwise formed to form a rough surface. Attached 40 to and slidably mounted thereon is a sleeve 12 which, at one end, carries a jaw 13 coacting with the jaw 11 and also having its face roughened, corrugated or serrated. Preferably the jaw 11 will have a concave 45 inner face and the confronting face of the jaw 13 will also be concave. Resting upon the sleeve 12 is a washer 14 and surrounding the rod or shank 10 is a coil spring 15, which bears upon the washer 14 at one end and 50 at the other end bears upon a collar 16 formed upon or attached to the shank 10.

The operation of this form of my invention will be obvious. The spring 15 will normally hold the jaws in closed position and, under these circumstances, the poker may be 60 used as an ordinary poker, the jaws 11 and 13 tapering to a point to this end. When it is desired to pick up a clinker or other object, it is only necessary to grasp the shank 10 with one hand, the sleeve 12 with 65 the other hand, and draw the sleeve upward against the force of the spring 13 and then engage the object to be picked up between the jaws 11 and 13 and release the sleeve.

For the purpose of readily shifting the 70 sleeve 12, it is provided with an outwardly projecting handle 17.

In Fig. 2 I show another form of the invention, which operates on precisely the same principle as the form previously described, but which is particularly adapted 75 to be used in large furnaces where the pokers or stoking irons are relatively long. In this case the poker proper comprises the shank 10^a and the jaw 11^a, the shank 10^a being provided with the collar 16^a. Slidably mounted upon the shank 10^a is a relatively short sleeve 12^a and connected to this sleeve is a longitudinally extending shank 18, constituting a handle, this shank being as long as 85 the shank 10^a. The spring 15^a surrounds the shank 10^a and bears against the sleeve and urges the jaw 13^a toward the jaw 11^a.

Under some circumstances, it is desirable to inclose the spring 15 within the sleeve 12^a and such a construction is illustrated in Fig. 3. In this form of the device the spring is a contractile spring, but otherwise than this and the positioning of the spring, there is no difference between this construction 90 and that shown in Figs. 1 and 2 and therefore the same reference characters are used.

In Fig. 1 the handle 17 is illustrated as passing through a slot 18 and being pivoted to the shank 10 at 19. Normally, therefore, 100 when the jaws 13 and 11 are closed, the handle will be in the dotted line position shown in Fig. 1, but by grasping the handle and turning it up to the full line position, the jaws will be caused to open. The handle 105 17^a in Fig. 3 is shown as rigidly mounted upon the tubular member 12.

Preferably I form the jaws 11 and 13 or 11^a and 13^a angular in cross section, as illustrated in Fig. 4, the upper jaw being sufficiently larger than the lower jaw as to fit 110 down over the lower jaw when the jaws are

2

in their closed positions, the interior faces of one or both jaws being toothed and the lower jaw being reversely angular relative to the upper jaw, so that when the lower jaw is closed against the upper jaw, it will fit closely within the upper jaw, thus making the jaws sufficiently narrow, when the jaws are closed, that they may be used as a poker. It will, however, be understood that these jaws might be made flat on their inside faces, or the jaws need not be tapered. The device can be used not only as a poker and for the purpose of picking up clinkers, but can be used for picking up all sorts of articles that fall into places where it is difficult for the hand to be inserted. It will be seen that the lever-like handle permits a stronger spring to be used than would otherwise be possible so that the device may be used for picking up relatively heavy articles, but yet be easily operated by a relatively weak person. The device is designed for the purpose of poking furnace fires, etc., and can be made to open 6 or 8 inches and thus engage the largest size of clinkers. It will be obvious that my device is very convenient, that it may be easily handled and cheaply constructed, and that while it performs all of the functions of an ordinary poker, yet it may be used for shifting lumps of coal over the fire bed, so as to bring the lumps over particular portions of the

fire, and that it may be used to remove clinkers from the fire bed.

Having described my invention, what I claim is:—

1. An implement of the character described comprising a shank having a jaw, a second jaw slidably mounted on the shank for movement toward and from the coacting jaw, said jaws being angular in cross section and fitting one within the other and being longitudinally tapered.

2. An implement of the character described comprising a shank having an angular jaw at one end, a sleeve slidably mounted on the shank for longitudinal movement and having a jaw coacting with the first named jaw, a handle having a curved portion extending through a slot in the sleeve and pivoted to the shank, and a spring urging the sleeve and shank in opposite directions and the jaws toward each other, a rotative movement of the handle in a position parallel with the sleeve acting to shift the shank and sleeve to a position where the jaws are open.

In testimony whereof I hereunto affix my signature in the presence of two witnesses.

FRANKLIN BINN.

Witnesses:

ANNA McDERMOTT,
JAMES H. APPLEGATE.
